UNITED STATES PATENT OFFICE

ANDREW M. JENSEN, OF STOCKTON, CALIFORNIA

ENVELOPE OPENER

Application filed July 26, 1927. Serial No. 208,514.

This invention relates to improvements in devices for opening envelopes, my principal object being to provide an implement for the purpose arranged to remove a narrow strip 5 of the envelope along any desired edge thereof so as to separate the adjacent sides of the envelope and allow them to be then split and the contents of the envelope to be removed.

The main advantage of my device over the 10 slitting blades ordinarily used for this purpose is that it is not necessary for the tool to be first inserted under the flap as must be done with such blades and which takes time to manipulate and is sometimes hard to do 15 if the flap is closely sealed throughout its extent.

A further object of the invention is to produce a simple and inexpensive device and yet one which will be exceedingly effective for 20 the purpose for which it is designed.

These objects I accomplish by means of such structure and relative arrangement of parts as will fully appear by a perusal of the following specification and claim.

25 In the drawing similar characters of reference indicate corresponding parts in the several views:

Fig. 1 is a perspective elevation of my device shown as operating upon an envelope.

30 Fig. 2 is a front elevation of said preferred form of the device.

Fig. 3 is a cross section on the line 3—3 of Fig. 2.

Referring now more particularly to the 35 characters of reference on the drawings, the device comprises a body 1 having a deep slot 2 cut in along one side of the body from end to end thereof. A groove 3 is cut in the bottom face of the slot parallel to the outer edge 40 of the body and is preferably nearer the bottom of the slot than the outer edge of the same. A handle 4 of suitable character projects outwardly from the side of the body opposite to the slot, said handle being set at 45 90 degrees to the longitudinal plane of the body, or at any other desired and suitable angle.

A cutting blade 5 is mounted in a slit cut in the body from the top thereof above the 50 slot and in transverse alinement with the

groove 3 and in the central transverse plane of said groove. The blade is removably clamped in position by set screws 6 mounted in the body. The implement is designed to take a rectangular blade, so that a safety 55 razor blade may be used for the purpose, as shown. This blade is set so that its cutting edge will be at an acute angle relative to the slot 2 and will project at one end into the groove 3. Since a blade of this type is apt 60 to have its opposed edges both sharp, and since the angle of setting of the blade causes the edge not in use to project above the body, I provide a removable hood H mounted on the body to cover said projecting edge and 65 so prevent possible harm to the user. By means of this construction it will be seen that if the edge of an envelope 7 is inserted at one end between the lips of the slot 2 in front of the blade, and so as to abut against the 70 back of the slot, a longitudinal movement of the implement relative to the envelope will cause said blade to cut through both thicknesses of the envelope adjacent its edge and remove a narrow strip 8 which of course 75 contains the connection previously had between said two thicknesses.

After the strip is removed from one end to the other of the envelope, the latter may be 80 freely opened so that its contents may be removed, as will be evident. The width of the strip thus cut is governed by the distance transversely of the implement from the back of the slot to the cutter, which distance is 85 sufficiently small so that there is no danger of cutting through the contents of the envelope. The cutting edge of the blade being angularly disposed to the line of movement of the envelope and tool, an efficient shearing cutting action is had. The groove 3 insures the blade depending below the bottom 90 of the slot 2, so that said blade cannot fail to cut through both thicknesses of the envelope.

From the foregoing description it will be 95 readily seen that I have produced such a device as substantially fulfills the objects of the invention as set forth herein.

While this specification sets forth in detail 100 the present and preferred construction of the

device, still in practice such deviations from such detail may be resorted to as do not form a departure from the spirit of the invention as defined by the appended claim.

5 Having thus described my invention what I claim as new and useful and desire to secure by Letters Patent is:

An envelope opener comprising a body having a longitudinal slot in one side and 10 a longitudinal slit intermediate its ends cut through from the top of the body to one face of the slot, a rectangular cutter blade projecting angularly through said slit so that one end extends across the slot at an acute 15 angle to the length thereof while the other end projects above the body, releasable clamping means preventing movement and removal of the blade, and a removable hood mounted on the top of the body to cover the projecting portion of the blade.

20 In testimony whereof I affix my signature.

ANDREW M. JENSEN.
